DANIEL S. ELLIS, OF HACKENSACK, NEW JERSEY

LOCOMOTIVE CROSSHEAD AND GUIDE CONSTRUCTION

Application filed February 18, 1929. Serial No. 340,993.

My invention relates to railway rolling stock and consists in a novel cross head and cross head guide construction for locomotives.

5 The main object of my invention is to maintain accurate interengagement between the cross head and its guide or guides and I secure this object by providing renewable parts where the same are subject to wear and by 10 providing adequate lubrication for the wearing surfaces.

An additional object of my invention is to facilitate the manufacture of the complete structure by novel elements preferably forming the main elements of one-piece castings with lubricant reservoirs formed integrally therein.

In the accompanying drawings which illustrate a selected embodiment of my invention—

Figure 1 is a side elevation of the assembled structure, some of the adjacent parts of the locomotive being indicated also.

Figure 2 is a top view of the upper cross head guide.

Figure 3 is a vertical longitudinal section through the same.

Figure 4 is a vertical transverse section taken on the line 4—4 of Figure 1.

Figure 5 is in part a side elevation and in part a vertical longitudinal section through the cross head and is made on a larger scale.

Figure 6 is a vertical transverse section through the cross head taken on the line 6—6 of Figure 5.

The cross head structure illustrated is associated with the usual locomotive cylinders 1 having pistons with rods 2, the cross head 3 being operatively connected to the drivers 4 by means of a connecting rod, not shown. The upper and lower cross head guides 5 and 6 respectively may be secured to the cylinder head, as indicated at 7, in the usual manner and secured to the locomotive frame (not shown) by suitable brackets 8 or in any other satisfactory way. The body portion of the upper guide 5 is preferably formed of a one-piece casting having integral depressions 9 formed therein at spaced points and adapted to hold a supply of lubricant. Preferably,

the depressions 9 are provided with screens 10 and cover plates 11, the cover plates fitting over suitable gaskets 12 and being secured to the guide by suitable bolts or screws 13. If desired, the lubricant reservoir 9 may be filled with suitable packing material 14 to prevent undue discharge of the lubricant from the reservoir. A renewable wear plate 15 is secured to the guide 5 by suitable rivets or bolts 16. Passageways 17 lead from reservoir 9 through wear plate 15 so as to discharge lubricant from the reservoir to the lower surface of the wear plate and these passageways 17 are arranged at spaced points along the guide so as to effect a uniform distribution of lubricant.

The lower cross head guide 6 is provided with a similar wear plate 18 but is not provided with any lubricant reservoir, the wear plate being lubricated from a suitable lubricant reservoir in the cross head 3.

The cross head 3 is preferably formed of a one-piece casting having a general U-shape but with an extra pocket forming wall 19 formed integrally therewith and extending along but spaced from one of the side walls of the body of the cross head and below the body of the cross head to form a lubricant reservoir. The upper portion of the cross head mounts renewable shoes 20 and the lower portion of the cross head is provided with spaced depending flanges 21 which mount a renewable shoe 22. The shoes 20 and 22 are secured to the cross head by suitable bolts 23 extending laterally through the adjacent cross head flanges or walls and the bolts for the lower shoe extending beneath the main portion of the lubricant reservoir. The lubricant reservoir, however, has an intermediate portion 24 projecting between flanges 21 and the adjacent bolts 23, as best shown in Figure 5, to a point adjacent to the horizontal portion of the shoe and a passageway 25 leads from this intermediate portion of the lubricant reservoir through the shoe to the wear plate 18 on which it is mounted.

The intermediate portion of the cross head is provided with the usual bearings 26 for the cross head pin (not shown) and the lubricant reservoir is formed arcuately about bearings

26 so as to provide additional capacity and also to facilitate renewing the supply of lubricant to the reservoir by presenting a filling opening 27 which will not be obstructed by the 5 laterally extending bearings.

The lubricant reservoir is provided with openings on its lower face through which packing material may be inserted and removed and suitable plugs 28 are removably 10 applied to these openings to seal the same against loss of lubricant.

The arrangement described provides spaced 15 points of lubrication for the engaging surfaces of the upper wear plate and the cross head shoe mounted thereon and provides a point of application of lubricant to the engaging surfaces of the lower wear plate and shoe which moves with the cross head. Since the 20 weight of the cross head is on the lower guide, the engaging surfaces of the upper shoe and wear plate do not require a great amount of lubricant and the comparatively shallow recesses in the guide provide adequate reservoirs. The formation of the reservoir in the 25 cross head provides a reservoir of substantially larger capacity for the relatively greater demands of the lower shoe and wear plate.

It will be noted that each of the shoes and 30 wear plates may be renewed when worn and this makes possible the maintaining of accurate fits between the cross head and guides, thereby eliminating any play between these parts. This construction also enables the 35 body of the cross head and guides to be made of cast metal and the interengaging parts to be made of relatively hard and expensive material.

Obviously, the details of my invention may 40 be modified substantially without departing from the spirit thereof and I contemplate the exclusive use of such variations in the construction as come within the scope of my claims.

I claim:

45 1. A locomotive cross head comprising in a one-piece casting an inner wall of U-shaped section, and an outer wall spaced from one side and the bottom of said U-shaped wall and forming therewith a pocket for lubricant, there being a discharge passageway through 50 the lower portion of said outer wall.

55 2. In a locomotive cross head, a body portion including a bearing for a cross head pin, a renewable shoe and a lubricant reservoir formed within said body portion and extending from below said bearing to the side thereof.

60 3. In a locomotive cross head, a body portion including a bearing for a cross head pin, and a lubricant reservoir formed within said body portion and extending from below said bearing to the side thereof and provided with a filling opening at the side of said bearing 65 whereby lubricant may be inserted into said

reservoir without removal of said cross head from its guides.

4. A locomotive cross head comprising a main body portion and a renewable shoe, said body portion having a lubricant reservoir 70 formed therein with an opening through which packing material may be inserted into said reservoir without the removal of said cross head from its guides, and a lubricant-tight closure for said opening.

75 5. In a locomotive cross head, a body portion including a bearing for a cross head pin, and a lubricant reservoir formed in said body portion below and at the side of said bearing and provided with a filling opening at the 80 side of said bearing and provided with another opening below said bearing for the insertion of packing material.

85 6. In a locomotive cross head, a U-shaped body portion adapted to receive a main connecting rod and to seat a cross head pin, there being a lubricant reservoir at one side of said body portion and extending beneath the connecting rod receiving portion of the head.

90 7. In a locomotive cross head, a body section and a renewable shoe, a lubricant reservoir at the side of said body section and extending into the lower portion of same, depending flanges on said body section through which bolts for securing a renewable shoe may 95 be passed, said reservoir including a restricted portion between said flanges for supplying lubricant to a shoe mounted thereon.

100 8. In combination, a locomotive cross head including a body portion, depending flanges thereon, a renewable shoe mounted on said flanges and spaced from said body portion and having a guide engaging surface, a lubricant reservoir formed in said body portion, and a passageway leading from said reservoir 105 through said shoe to said surface.

110 9. In combination, a locomotive cross head including a body portion and a renewable shoe thereon having a guide engaging surface, a reservoir formed in said body portion, and a passageway from said reservoir through said shoe to said surface.

115 10. In a locomotive cross head guide, a main portion formed of a one-piece casting with an integral lubricant reservoir, and a renewable wear plate secured to said main portion, there being a lubricant passageway from said reservoir to the cross head engaging surface of said wear plate.

120 11. In combination, locomotive upper and lower cross head guides, renewable wear plates thereon, a cross head, renewable shoes secured thereto and mounted on said wear plates, lubricant reservoirs in said upper guide and said cross head, a passageway for lubricant leading from the reservoir in said upper guide to the interengaging surfaces of the wear plate and shoe mounted thereon, and a passageway leading from the reservoir in said crosshead to the interengaging surfaces 125 130

of the lower shoe and the wear plate on which it is mounted.

12. In combination, an upper cross head guide having a plurality of lubricant reservoirs formed therein and spaced longitudinally thereof, a lower cross head guide, a crosshead mounted on said guide and having a lubricant reservoir formed therein, means for discharging lubricant from said first mentioned reservoir to the interengaging surfaces of said cross head and upper guide at points spaced longitudinally of the latter, and means for discharging lubricant from said cross head reservoir to the interengaging surfaces of said cross head and lower guide beneath said cross head only.

13. A locomotive cross head comprising a body member including a bearing for a cross head pin, and a renewable shoe there being a lubricant reservoir formed in said body member and occupying space within said body and partially surrounding said bearing, said reservoir being separated from said bearing by a wall of said body member.

14. A locomotive cross head having a general U-shaped cross section, cross head pin bearings in the legs of said body, a pocket for lubricant formed on one leg of said cross head abreast of said bearings, and a passageway for lubricant leading from said pocket beneath said bearings to discharge lubricant.

15. In combination, a locomotive cross head and a cross head guide, said cross head comprising a main body portion and a renewable shoe, said body portion being adapted to be secured to the piston rod of the locomotive, interengaging sliding surfaces between said shoe and guide, and a lubricant reservoir contained in said cross head body portion for lubricating said surfaces.

In testimony whereof I hereunto affix signature this 7 day of February, 1929.

DANIEL S. ELLIS.
